UNITED STATES PATENT OFFICE.

FRANK E. FITCH, OF ROCHESTER, NEW YORK, ASSIGNOR OF TWO-THIRDS
TO HERMON V. HOAG, JR., OF SMITHVILLE FLATS, NEW YORK, AND
JOSEPH H. FITCH, OF ROCHESTER, NEW YORK.

DESIGN FOR A VENDING-MACHINE CASE.

SPECIFICATION forming part of Design No. 35,702, dated February 4, 1902.

Application filed December 2, 1901. Serial No. 84,477. Term of patent 14 years.

To all whom it may concern:

Be it known that I, FRANK E. FITCH, a citizen of the United States, residing at Rochester, in the county of Monroe and State of New York, have invented and produced a new and original Design for Vending-Machine Cases, of which the following is a specification, reference being had to the accompanying drawings, forming part thereof.

Figure 1 is a plan view of the vending-machine case, showing my new design. Fig. 2 is a perspective elevation of the case seen as indicated by arrow 2 in Fig. 1. Fig. 3 is a perspective view seen as indicated by arrow 3 in Fig. 1.

As shown in the drawings, my design consists of a straight prismatic shaft A, square in cross-section, rising centrally from a rectangular block or base B of larger horizontal dimensions than those of the shaft. The upper part or end C of the shaft is tapered to a point, being prismatic in form, with square base, as shown. Below the base B is a horizontal rectangular part C, slightly larger in

horizontal dimensions than the said base, having four inclined faces D, the whole being supported upon downwardly-projecting parts or feet E, one at each corner of the part C. The upper faces F and G of the parts B and C, respectively, are plain and horizontal. Two opposite vertical faces of the base B are formed with arched openings, one being shown at H immediately above the upper surface of the part C. At the upper part of the front face of the base are two shafts or arms I I, projecting at right angles with the face of the base.

Having described my invention, what I claim as new, and desire to secure by Letters Patent, is—

The design for a vending-machine case, as herein shown and described.

In testimony whereof I have signed my name to this specification in the presence of two subscribing witnesses.

FRANK E. FITCH.
